REFRIGERATION

Elmer W. Zearfoss, Jr., Philadelphia, Pa., assignor, by mesne assignments, to Philco Corporation, Philadelphia, Pa., a corporation of Pennsylvania

Application November 30, 1944, Serial No. 565,842

12 Claims. (Cl. 62—115)

1

The present invention relates to refrigeration and particularly to refrigerant compression systems. More specifically, the invention pertains to a novel method and system for obtaining multi-stage compression with a single piston and cylinder.

The advent of domestic refrigerators having one or more evaporator portions working within the zero temperature range, has given rise to numerous problems. Notable among these, is the problem of adequately compressing the evaporated or expanded refrigerant. Adequate compression may, of course, be obtained by redesigning the motor-compressor units now in use, to increase the capacity or volumetric displacement of such units. This, however, necessitates enlarging the overall dimensions of the unit as well as increasing the size and power of the motor required to drive the compressor, with the result that the unit requires additional space for its mounting within the refrigerator cabinet structure, which space could be used to greater advantage for refrigerated storage. The use of known multi-stage compressor units embodying multiple pistons and cylinders, still have the disadvantages above mentioned, in that the added pistons and compression chambers add to the size of the units and demand relatively large and powerful motors.

It is an object of this invention to provide a method and system whereby, in domestic refrigerators of the special type above referred to, the evaporator or expanded refrigerant may be compressed adequately by means of commercially known motor-compressor units now commonly used in conventional domestic refrigerators, without necessitating the redesigning of such units and without requiring material changes in the basic structure thereof, so that no more space than has heretofore been required is needed to mount the units in the refrigerator cabinets.

It is also an object of the invention to provide a system for compressing evaporated or expanded refrigerant to the required pressure to assure its condensation for recirculation in an evaporator intended to cool a space at low freezing temperatures, the system being such that compression of the refrigerant is effected in two stages by means of the single piston and cylinder of a type of motor-compressor unit now available on the market.

Another object of the invention is the provision of a refrigerant compressing system for use in a refrigerating circuit intended to cool a space at low freezing temperatures, said system employing a type of compressor heretofore used

2

for single compression to perform multi-stage compression.

Still another and more specific object of the invention is to provide a method of and system for obtaining two-stage compression by means of the generally known single-stage hermetic motor-compressor unit which heretofore has been commonly used in ordinary domestic refrigerating circuits.

10 The invention is further characterized by the provision of a refrigerant two-stage compression system utilizing a compressor of the single compression chamber type, which, in addition to its primary function of adequately compressing the refrigerant, provides a space wherein the pressure of the refrigerant may be raised to the proper value between the first and second stages for the purpose of effecting two-stage compression.

Other objects and characteristic features of 20 the invention will appear from the following description and from the accompanying drawings, in which:

Figure 1 is a semi-diagrammatic representation 25 of the system of the invention and its method of operation; and

Figure 2 is a transverse vertical sectional view 30 of a hermetic motor compressor unit incorporating the features of the invention and illustrating a refrigerating circuit connected therewith.

35 As illustrated in the drawings, the refrigerant compression system is included in the refrigerant circuit which, conventionally, contains an evaporator 1 and a condenser 2, a suitable refrigerant flow restrictor 3 being interposed between said evaporator and condenser. The compression system basically comprises a compression chamber C, a hermetically sealed zone S and pressure responsive means M, the latter being adapted to 40 control the initiation of the first and second stage operations of said system.

In accordance with the method of this invention, during first stage operation of the system, expanded or evaporated refrigerant at suction pressure, say, 15 pounds per square inch absolute, is drawn from the evaporator 1 into the compression chamber C, and is pumped from said chamber into the hermetically sealed zone S against interstage pressure of minimum value, say, 50 pounds per square inch absolute, until the pressure in the latter is raised to a predetermined maximum interstage value, say, 55 pounds per square inch absolute, whereupon the pressure responsive means M is actuated to initiate the second stage operation of the compression system. In this second stage operation, the re-

frigerant from the zone S is admitted at inter-stage pressure into the compression chamber C and is discharged therefrom into the condenser 2 at a discharge pressure of say, 180 pounds per square inch absolute. The second stage operation is continued until the pressure within the zone S is reduced again to the aforesaid minimum interstage pressure, whereupon the pressure responsive means M operates to reinitiate first stage operation thus starting another cycle in the two-stage function of the compression system.

As shown in the drawings, the chamber C is defined by a cylinder 4 in which a piston 5 is mounted for reciprocatory motion through operation of a suitable motor 6 (Fig. 2), and the zone S is defined by a housing 7 which, as shown in Fig. 2, may be the motor-compressor housing. Also as shown in the drawings, the pressure responsive means M preferably takes the form of a multiple valve mechanism comprising a valve casing 8 and a pair of spaced interconnected valve members 9 and 10, respectively, mounted for axial movement within and longitudinally of said valve casing. Formed within the walls of the valve casing 8 and adapted to accommodate the valve members 9 and 10, are relatively spaced co-axial recesses 11 and 12 each having oppositely disposed valve seats 13 and 14. In mounting the valve members 9 and 10 in the manner stated, three distinct non-communicating spaces 15, 16 and 17 are provided within the valve casing 8.

The respective valve members are adapted to seat selectively on the valve seats 13 or 14, and it is to be noted that the said members seat simultaneously on their respective valve seats 13, and simultaneously also on their respective valve seats 14. For that purpose, there is provided a relatively heavy compression spring 18 which normally acts on the valve member 9 to urge the same into engagement with the seat 13. In the present instance the valve members 9 and 10 are rigidly connected by a rod 19 so that they move together as a unit between the respective seats.

With reference to the drawings, it is pointed out that when the valve members 9 and 10 are seated on their respective seats 13, that is, in the position shown in full lines, the system will function for first-stage operation. In this position of the valve members, a casing port 21, connected with a conduit 22 leading from the refrigerant evaporator 1, is in communication with a port 23 which is connected through a conduit 24 with the valved intake port 24a of compression chamber C; and a casing port 25 connected with a conduit 26 leading from the valved exhaust port 26a of said chamber C is in communication with a port 27 which is connected through a conduit 28 with the hermetically sealed zone S. Referring again to the drawings, it will be noted that when the valve members 9 and 10 are seated on their respective seats 13, that is, in the position shown in dotted lines, the system will function for second stage operation. In this latter position of the valve members, port 23 is in communication with port 27, and port 25 communicates with a port 29 which is connected through a conduit 30 with the refrigerant condenser 2.

Since the system is a closed circuit controlled by the valve means M, it will be appreciated that a pressure differential may be maintained at all times on opposite sides of the valve members 9 and 10, and in accordance with the invention, the system has three distinct pressure sides, that is, a low pressure side P₁, an intermediate pressure side P₂, and a high pressure side P₃. During first

stage operation of the system, the low pressure side P₁ extends from the restrictor 3 through the evaporator 1, conduit 22, and port 21 into valve space 15, thence through port 23 and conduit 24 into the compression chamber C up to the exhaust valve 26a thereof; the intermediate pressure side P₂ extends from said exhaust valve through conduit 26 and port 25 into the valve space 16, thence through port 27, conduit 28 and into the hermetically sealed zone S; and the high pressure side P₃ extends from the valve space 17 through port 29, conduit 30, condenser 2 and conduit 32 up to the restrictor 3.

During second-stage operation of the system, when the valve members 9 and 10 occupy the alternative positions establishing communication between ports 23 and 27 and between ports 25 and 29, then the conduit 24 and compression chamber C up to its exhaust valve 26a become parts of the intermediate pressure side, while conduit 26 between said exhaust valve 26a and port 25 becomes a part of the high pressure side.

It will be understood, therefore, that the forces exerted in one direction on the valve members 9 and 10, must be sufficient to overcome the pressure forces exerted on said members in the other direction while the system functions in first-stage operation to build up the pressure in the intermediate pressure side P₂ to the predetermined maximum interstage value, and that this pressure differential upon the valve unit must be reversed in order to initiate and maintain second-stage operation, and again reversed when the intermediate pressure has dropped to the minimum in order to reinitiate the first-stage operation.

To summarize the operation of the system as far as described, let it be assumed that the condition is such that the interstage pressure within the zone S and therefore in the valve space 16, 40 has been reduced to its minimum value, say, 50 pounds per square inch absolute, and that the force of spring 18 together with the force of the fluid pressure within the valve space 15 are sufficient to move the valve unit to first-stage position, that is, to the position shown in full lines in the drawings. The flow of refrigerant is then, as indicated by the solid arrows in Fig. 1, that is low pressure gaseous refrigerant, admitted into the compression chamber C through conduit 22, 50 port 21, valve space 15, port 23 and conduit 24, and is discharged at increased pressure into the hermetically sealed zone S through conduit 26, port 25, valve space 16, port 27 and conduit 28. Continued pumping of the refrigerant causes the 55 pressure in the zone S to gradually increase until the interstage pressure in said zone, and therefore in the valve space 16, reaches its predetermined maximum value, at which point the force exerted by the fluid pressures acting on the relatively large piston 9 is sufficient to overcome the combined forces of the spring 18 and the fluid pressures on the relatively small valve member 10, thus causing the valve unit to move to its second-stage position, that is, the position shown 60 in dotted lines in the drawings. The flow of the refrigerant is then, as indicated by the broken arrows in Fig. 1, that is, gaseous refrigerant at interstage pressure, permitted to flow into the compression chamber C through conduit 28, port 27, valve space 16, port 23 and conduit 24, and is discharged at elevated pressure into the condenser through conduit 26, port 25, valve space 17, port 29 and conduit 30. The high pressure gaseous refrigerant gives up its heat in the condenser and condenses therein to return, as liquid,

to the evaporator. This second-stage operation of the system continues until the interstage pressure within the zone S and valve space 18 is reduced to the predetermined minimum value, whereupon the opposing pressures on the valve members 9 and 10 become unbalanced in a direction causing the valve unit to return to the initial position and to thereby initiate another first-stage operation.

In order to minimize the force effect on the valve member 10, the area of the valve member 9 should be considerably larger than the area of said member 10. Moreover, it is to be understood that the "spring rate" of spring 18 should have a low value, so that the changes in its length, which occur with movements of the valve members 9 and 10 from one seated position to another, does not materially affect the force exerted by said spring on said members.

In order to assure proper seating of the valve members 9 and 10 and also to preclude unseating of the members during the periods when the interstage pressure is in process of change between the aforesaid limits, suitable detent means, such as shown at 34, may be provided to engage the edge portions of the valve member 9, said detent holding the valve unit against movement until such time as one or other of said limits is reached and the pressure conditions are then such as to effect a shifting of the valve unit from one to the other of its alternative seated positions. The movement of the valve unit from one of said positions to another will occur almost instantaneously.

Provision is made also for balancing the weight of gaseous refrigerant handled by the compressor during the first and second stage operations, thus equalizing the number of strokes required for and the amount of work performed in said stages. In the embodiment shown in the drawings, this is accomplished by providing a port 35 extending through the side wall of the compressor cylinder 4 to establish communication between the compressor chamber C and the hermetically sealed zone S, the connection including a casing 36, a tube 37, and a valve 38 which controls passage of gaseous refrigerant through the port as hereinafter described.

During first-stage operation, when gaseous refrigerant at suction pressure, say, 15 pounds per square inch absolute, is drawn into the compression chamber C, the valve 38 remains closed because then the pressure in said compression chamber is lower than the pressure in the casing 36 which is in communication with the zone S. The zone S, as previously set forth, is maintained at an interstage pressure of between 50 and 55 pounds per square inch absolute. During second-stage operation, when gaseous refrigerant at interstage pressure is admitted to the compression chamber C by movement of the piston 5 through its intake stroke D (Fig. 1), the valve 38 still remains closed because then the pressure on both sides of this valve is equal. However, the valve 38 opens as the compression stroke begins due to the increased pressure in said chamber so that gaseous refrigerant is bled back into the zone S during movement of the piston through the initial part D₁ of the discharge stroke. Movement of the piston over the part, D₂, of the discharge stroke which remains after the port 35 is covered, effects the normal second-stage compression. By locating the port 35 so that a given part of the more highly compressed gaseous refrigerant in second-stage operation is bled away

as described above, the weight of the refrigerant handled during the two stages may be substantially balanced and, therefore, the work done per stroke and the number of strokes required for each stage substantially equalized.

With reference to Fig. 2, which illustrates the adaptation of the compression system to a well-known type of hermetic motor-compressor unit, the tube 37 preferably opens into the zone S at 10 a point above the oil level 39 so that direct communication is established between said zone and the casing 36 which encloses the valve 38.

Also, as shown in Fig. 2, an intercooler 40 of known structure may be included in the system 15 to cool the gaseous refrigerant as it is pumped into or out of the zone S. In this manner, it is possible to remove the heat of first-stage compression thereby increasing the efficiency of the system.

Moreover, as illustrated in Fig. 2, the system 20 may, and preferably does, include an overload cut-off arrangement generally indicated at 41 which functions to prevent the imposition of excessive load on the motor, particularly during 25 "pull down" periods, that is, during those periods when the evaporator 1 is working at abnormally high temperatures such as is the case, for instance, during defrosting cycles. The overload cut-off arrangement 41 preferably comprises a 30 valve 42 mounted in the suction conduit 22 to control the flow of refrigerant therethrough. This valve 42 may be automatically actuated in response to variations in pressure within the system. For that purpose a bellows 43, see Fig. 2, 35 is connected, through the conduit 28 in the present instance, with that portion of the system included in the intermediate pressure side P₂. In practice the bellows 43 is adjusted, by means for example of a suitable regulating device 44, so as 40 to be actuated if and when the pressure in the intermediate pressure side P₂ rises above normal operating pressure, say to 60 pounds per square inch absolute. Connected with the bellows 43 to be operated thereby is a switch 45 adapted to open 45 and close on electrical circuit 46 in which is included a solenoid 47 operatively connected to the actuating member 48 of the valve 42. When, therefore, the pressure in the intermediate pressure side of the system rises abnormally, as would 50 occur during a "pull down" period, when the bellows 43 will expand moving the switch 45 into position for closing the circuit 46 and energizing the solenoid 47 to close the valve 42; as soon as 55 normal operating pressure is re-established in the system, the bellows will collapse moving the switch 45 into position for opening the circuit 46 to de-energize the solenoid 47 and to thereby open the valve 42.

In effect, the overload cut-off arrangement 41 60 functions to control the pressure responsive means M in such manner that the interstage pressure, during "pull down" or high temperature periods, never exceeds a predetermined top value, say, 60 pounds per square inch absolute. 65 This point, therefore, establishes the maximum work done during both first and second stage compression.

It will be apparent that the invention makes 70 possible efficient multi-stage compression by means of a single piston and cylinder assembly, and that such multi-stage compression may be obtained by means of a known conventional type of motor compressor unit designed and heretofore used solely for single compression operation.

75 It will be understood that the invention is not

limited to the specific structural embodiments herein shown and described, and that such embodiments are subject to modification within the scope of the appended claims.

I claim:

1. In refrigeration, the method which comprises subjecting low pressure gaseous refrigerant to a first-stage compression in a compression chamber to bring such refrigerant to an elevated interstage pressure, collecting the gaseous refrigerant at said interstage pressure in an hermetically sealed zone, subsequently returning the gaseous refrigerant at the elevated pressure from said zone to the compression chamber for a second-stage compression therein to a relatively high discharge pressure, and bleeding a portion of said refrigerant from the compression chamber so as to reduce the quantity of gas subjected to the second-stage compression.

2. In refrigeration, the method which comprises compressing low pressure gaseous refrigerant in a compression chamber to an elevated interstage pressure, discharging the compressed gaseous refrigerant into a hermetically sealed zone, subsequently returning the compressed gaseous refrigerant from said zone to said chamber, compressing such refrigerant to a discharge pressure in excess of the said interstage pressure, and diverting a portion of the refrigerant from the compression chamber to said zone so as to reduce the quantity of the gas subjected to the second compression.

3. In refrigeration, the method which comprises admitting gaseous refrigerant at suction pressure to a compression chamber, compressing the refrigerant in said chamber to interstage pressure and discharging the compressed gaseous refrigerant into an hermetically sealed zone, thereafter returning compressed gaseous refrigerant from said zone to said chamber and compressing such refrigerant to discharge pressure in excess of the said interstage pressure, and bleeding a portion of said refrigerant from the compression chamber so as to reduce the quantity of the refrigerant subjected to the last-mentioned compression.

4. In the operation of a refrigerating system including an evaporator, a condenser, a compressor of the type having a single compression chamber, and conduit means interconnecting said evaporator, condenser and compressor for flow of refrigerant therethrough, the method which comprises first, initiating a flow of expanded gaseous refrigerant at suction pressure from said evaporator to the compressor and into the compression chamber thereof, compressing such gaseous refrigerant in said chamber to an interstage pressure and collecting the compressed gaseous refrigerant in an hermetically sealed zone until the pressure therein reaches a predetermined maximum value, then interrupting the flow of the gaseous refrigerant from the evaporator to the compressor and initiating a return flow of the compressed gaseous refrigerant from said zone to said compressor and into the compression chamber thereof, further compressing the gaseous refrigerant in said chamber to a relatively high discharge pressure and discharging gaseous refrigerant at such discharge pressure into the condenser to be liquefied therein for circulation as liquid from the condenser to the evaporator.

5. In the operation of a refrigerating system including an evaporator, a condenser, a compressor of the type having a single compression

chamber, and conduit means interconnecting said evaporator, condenser and compressor for flow of refrigerant therethrough, the method which comprises first, initiating a flow of expanded gaseous refrigerant at suction pressure from said evaporator to the compressor and into the compression chamber thereof, compressing such gaseous refrigerant in said chamber to an interstage pressure and collecting the compressed gaseous refrigerant in an hermetically sealed zone, then interrupting the flow of the gaseous refrigerant from the evaporator to the compressor and initiating a return flow of the compressed gaseous refrigerant from said zone to said compressor and into the compression chamber thereof, bleeding a portion of such gaseous refrigerant from said chamber and back into said zone, compressing the remaining portion of such gaseous refrigerant in the chamber to a relatively high discharge pressure and discharging gaseous refrigerant at such discharge pressure into the condenser to be liquefied therein for circulation as liquid from the condenser to the evaporator.

6. In the operation of a refrigeration system including an evaporator, a condenser, a motor compressor unit of the type having a hermetically sealed housing enclosing said unit, and conduit means interconnecting said evaporator, condenser, and motor compressor unit for the flow of refrigerant therethrough, the method which comprises first, initiating a flow of expanded gaseous refrigerant at suction pressure from said evaporator to the compressor, compressing such gaseous refrigerant in said compressor to an interstage pressure, and discharging the compressed gaseous refrigerant into the motor compressor housing until the pressure therein reaches a predetermined maximum value, then interrupting the flow of gaseous refrigerant from the evaporator to the compressor and initiating a return flow of the compressed gaseous refrigerant from said housing to the compressor, further compressing such gaseous refrigerant in the compressor to a relatively high discharge pressure and discharging the refrigerant at such discharge pressure into the condenser to be liquefied therein for circulation as liquid from the condenser to the evaporator, re-establishing the flow of low pressure gaseous refrigerant from the evaporator to the compressor when the pressure in said housing reaches a predetermined minimum value, and repeating the steps as specified.

7. In a refrigerant system, a compressor, a hermetically sealed zone, means for circulating refrigerant between said compressor and zone, said circulating means including a first conduit for admitting refrigerant to said compressor, a second conduit for discharging refrigerant from said compressor, a third conduit for both admitting refrigerant to and discharging refrigerant from said zone, a valve casing in communication with said three conduits, and valve means in said casing responsive to pressure variations in the system for establishing communication between said third conduit and the said first and second conduits selectively.

8. In a closed refrigerant circuit comprising a refrigerant compressor having a single compression chamber provided with an intake port and exhaust port, means for admitting expanded refrigerant at suction pressure into said chamber through the intake port thereof, an hermetically sealed zone maintained at an interstage pressure in excess of said suction pressure, conduit means connecting said zone with said ports, a

pressure responsive device associated with said conduit means and operable to initiate the first and second stage compression operations of the system in accordance with predetermined minimum and maximum interstage pressure values in said zone, and means for condensing refrigerant compressed to a discharge pressure in excess of said interstage values, said pressure responsive device including a valve structure constantly exposed to the pressure within said zone and operative when the interstage pressure in said zone is reduced to the predetermined minimum value to establish communication between the expanded refrigerant admitting means and the compression chamber intake port and between the compression chamber exhaust port and the hermetically sealed zone, thereby initiating the first stage compression operation, and when the interstage pressure in said zone is increased to the predetermined maximum value, to interrupt communication between the expanded refrigerant admitting means and the compression chamber intake port and to establish communication between said intake port and the hermetically sealed zone and also between said compression chamber exhaust port and the refrigerant condensing means, thereby initiating the second-stage compression operation.

9. In a closed refrigerant comprising a refrigerant compressor having a single compression chamber provided with an intake port and an exhaust port, means for admitting expanded refrigerant at suction pressure into said chamber through the intake port thereof, a hermetically sealed zone maintained at an interstage pressure in excess of said suction pressure, conduit means connecting said zone with said ports, a pressure responsive device associated with said conduit means and operable to initiate the first and second stage compression operations of the system in accordance with predetermined minimum and maximum interstage pressure values in said zone, and means for condensing refrigerant compressed to a discharge pressure in excess of said interstage pressure, said pressure responsive device including a valve structure constantly exposed to the pressure within said zone and operative when the interstage pressure in said zone is reduced to the predetermined minimum value to establish communication between the expanded refrigerant admitting means and the compression chamber intake port and between the compression chamber exhaust port and the hermetically sealed zone, thereby initiating the first stage compression operation, and when the interstage pressure in said zone is increased to the predetermined maximum value to interrupt communication between the expanded refrigerant admitting means and the compression chamber intake port and to establish communication between said intake port and hermetically sealed zone and between said compression chamber exhaust port and the refrigerant condensing means, thereby initiating the second-stage compression operation, and means for bleeding a portion of the refrigerant from said chamber to said zone during the second stage compressing operation.

10. In a multi-stage refrigerant compressing system utilizing a motor-compressor unit of the type having a hermetically sealed housing enclosing said unit, means for circulating refrigerant between said compressor and the interior of said housing, said circulating means including a first conduit for admitting refrigerant to the compressor, a second conduit for discharging re-

frigerant from the compressor, a third conduit for both admitting refrigerant to and discharging refrigerant from the housing, a valve casing in communication with said three conduits, and a valve in said casing responsive to pressure variations in the system for establishing communication between said third conduit and one of said first and second conduits selectively while interrupting communication between said third conduit and the other of said first and second conduits.

11. In a refrigerating apparatus including an evaporator and a condenser, a two-stage refrigerant compressing system comprising a compressor of the type having a single compression chamber provided with a valved intake port and a valved exhaust port, an hermetically sealed zone, conduit means interconnecting said evaporator, condenser, compressor and zone to provide a closed circuit for the circulation of refrigerant, an interposed device including valve means movable selectively into two positions in response to pressure variations in the system, said valve means being operative in one position to establish communication between the evaporator and the intake port of the compression chamber and between the exhaust port of said chamber and the hermetically sealed zone, and in the other position to establish communication between said zone and the intake port of said compression chamber and between the exhaust port and the condenser.

12. In a refrigerating apparatus including an evaporator and a condenser, a two-stage refrigerant compressing system comprising a compressor of the type having a single compression chamber provided with a valved intake port and a valved exhaust port, a hermetically sealed zone, conduit means interconnecting said evaporator, condenser, compressor, and zone for the circulation of refrigerant therethrough, an interposed device operable to initiate first and second stage operations in the system, said device including valve means movable selectively into two positions in response to pressure variations in the system, said valve means being operative in one of said positions to establish communication between the evaporator and the intake port of the compression chamber and between the exhaust port of said chamber and the hermetically sealed zone, thereby initiating first stage operation, and in the other of said positions to establish communication between said zone and the intake port of said compression chamber and between the exhaust port and the condenser, thereby initiating second-stage operation, means for bleeding a portion of the refrigerant from said chamber back to said zone during the second-stage compressing operation, and pressure actuated means included in said conduit means for interrupting flow of refrigerant from the evaporator to the condenser when pressure in the system attains an abnormally high value.
